[57] CLAIM

The ornamental design for the large size rechargeable flashlight, as shown and described.

DESCRIPTION

FIG. 1 is a perspective view of a large size rechargeable flashlight showing my new design;

FIG. 2 is a top plan view thereof;

FIG. 3 is a side elevational view thereof;

FIG. 4 is a bottom plan view thereof;

FIG. 5 is a front end elevational view thereof; and,

FIG. 6 is a rear end elevational view thereof.

The opposite side elevational view is a mirror image of FIG. 3.

The broken lines are shown for illustrative purposes only and form no part of the claimed design.
